UNITED STATES PATENT OFFICE

95,029

DESIGN FOR A WEIGHING SCALE OR ARTICLE OF SIMILAR NATURE

Thomas B. Flanagan, Columbus, Ohio, assignor
to The Exact Weight Scale Company, Colum-
bus, Ohio, a corporation of Ohio

Application July 19, 1934, Serial No. 52,634

Term of patent 14 years

To all whom it may concern:

Be it known that I, Thomas B. Flanagan, a citizen of the United States of America, residing at Columbus, in the county of Franklin and State of Ohio, have invented a new, original, and ornamental Design for a Weighing Scale or Article of Similar Nature, of which the following is the specification, reference being had to the accompanying drawing, forming a part hereof.

Figure 1 is a perspective view of a weighing scale, showing my new design.

Figure 2 is a plan view on a smaller scale of the weighing scale shown in Figure 1.

I claim:

The ornamental design for a weighing scale or article of similar nature, as shown.

THOMAS B. FLANAGAN.
